CLAIM

The ornamental design for a drying mat as shown and described.

DESCRIPTION

FIG. 1 is a perspective view of a drying mat of our new design.

FIG. 2 is a front view thereof.

FIG. 3 is a back view thereof.

FIG. 4 is a right side view thereof.

FIG. 5 is a left side view thereof.

FIG. 6 is a top view thereof; and,

FIG. 7 is a bottom view thereof.

The ornamental design which is claimed is shown in solid lines in the drawings. Broken lines are for illustrative purposes only and form no part of the claimed design.
